Primary Examiner — Freda S Nunn(74) *Attorney, Agent, or Firm* — Matthew M. Googe;
 Robinson IP Law, PLLC(57) **CLAIM**

The ornamental design for a beverage insulating sleeve, as shown and described.

DESCRIPTION

FIG. 1 is a front perspective view of the beverage insulating sleeve showing my new design;

FIG. 2 is a front elevational view thereof;

FIG. 3 is a rear elevational view thereof;

FIG. 4 is left elevational view thereof;

FIG. 5 is a right elevational view thereof;

FIG. 6 is a top view thereof;

FIG. 7 is a bottom view thereof; and,

FIG. 8 is a view of the beverage insulating sleeve in an open configuration with the beverages shown within the beverage insulating sleeve, the beverage insulation sleeve including a plurality of snaps to accommodate various sized beverage containers.

The thin solid lines in the views have been provided for the purpose of illustrating the uniformity of the planar surfaces and the contour of the curved surfaces and are not a claimed surface pattern.

The structural features depicted by broken lines in the drawing have been provided for the purpose of illustrating portions of the beverage insulating sleeve that form no part of the claimed design.
